(57) **CLAIM**

The ornamental design for a modular cabinet, as shown and described.

DESCRIPTION

FIG. 1 is a left front perspective view of the design of the modular cabinet;

FIG. 2 is a front elevational view thereof. The ornamental design is not visible in a rear view, top plan view or bottom view; and,

FIG. 3 is an enlarged view of the pattern on the modular cabinet doors of the embodiment of FIG. 1.

The characteristic feature of the ornamental design resides in the use of a pattern on the modular cabinet doors.

Those portions of modular cabinet in broken lines, specifically the surfaces of the modular cabinet at the top and bottom edges of the doors and surfaces extending back from the doors including other surfaces of the modular cabinet are for illustrative purposes only and are not part of the claimed invention.
